US00D958755S

(12) **United States Design Patent** (10) **Patent No.:** **US D958,755 S**
(45) **Date of Patent:** **** Jul. 26, 2022**

(54) **SOCKET**

(71) Applicant: **Dongguan Wontravel Electric Co., Ltd., Guangdong (CN)**

(72) Inventor: **Liangguan Lin, Guangdong (CN)**

(**) Term: **15 Years**

(21) Appl. No.: **29/794,900**

(22) Filed: **Jun. 15, 2021**

(51) LOC (13) Cl. **13-03**

(52) U.S. Cl.

USPC **D13/139.7**

CLAIM

The ornamental design for a socket, as shown and described.

DESCRIPTION

FIG. 1 is a front elevational view of a socket showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a second perspective view thereof;

FIG. 9 is a third perspective view thereof; and,

FIG. 10 is a fourth perspective view thereof.

The broken lines shown in the drawings illustrate portions of the socket that form no part of the claimed design.

1 Claim, 10 Drawing Sheets
